UNITED STATES PATENT OFFICE.

BENJAMIN B. CONRAD AND FRANK SANDER, OF NEW YORK, N. Y., ASSIGNEES TO AMERICAN NUMBERING MACHINE COMPANY, OF BROOKLYN, NEW YORK, A CORPORATION OF NEW YORK.

TYPOGRAPHIC NUMBERING-MACHINE.

No. 920,917.

Specification of Letters Patent.

Patented May 11, 1909.

Application filed March 1, 1909. Serial No. 480,772.

To all whom it may concern:

Be it known that we, BENJAMIN B. CONRAD and FRANK SANDER, citizens of the United States, residing at Brooklyn, in the county of Kings, city and State of New York, have invented certain new and useful Improvements in Typographic Numbering-Machines, of which the following is a clear, full, and exact description.

10 This invention relates to numbering machines, more particularly that type of machine known as a typographic machine. A typographic machine is one adapted to be locked up with type, and to have its number 15 wheels actuated automatically upon the successive operations of a printing press.

The invention relates particularly to a machine of the type set forth in United States Patent 910,866, dated January 26th, 20 1909, and issued to these applicants' assignee.

25 The present invention is for a machine which has many of the characteristics of the machine of the patent referred to, but contains certain improvements in means for securing the detachable plunger and its casing to the main frame; and also in details of construction of the said plunger casing.

The scope of our invention will be pointed 30 out in the claims.

In the accompanying drawings, Figure 1 is a side elevation of a machine constructed according to our invention. Fig. 2 is a left-hand end view of Fig. 1. Fig. 3 is a section 35 of a part of the machine on line 3—3 Fig. 2. Fig. 4 is a perspective view of the plunger and plunger casing. Fig. 5 is a top plan of so much of the machine as is shown in Fig. 3. Fig. 6 is a left-hand end view of the main 40 casing with the plunger and plunger casing removed. Fig. 7 is a perspective view of the plunger casing. Fig. 8 is a perspective view of the respective jaws on the main frame, which are adapted to receive and hold the 45 plunger and plunger casing, and Fig. 9 is a side elevation of a part of the main frame, and of the plunger and plunger casing, showing the position of the parts upon the insertion of the plunger and plunger casing into 50 the main frame.

As shown in the drawings, 1 is the U shaped main frame; 2 is a shaft passing therethrough; 3 is the ordinary pawl swing; 4 are the number wheels; 5 are the usual de-

taining pawls such as used in any numbering machine.

The main frame 1 is provided with two projecting jaws 6, having elongated slots 7, therein, and communicating passages 8 leading from the outer edge of said jaws to the elongated slots 7. The shaft 2 extends through an opening in the main frame between the two jaws, and carries a rocking arm 13 provided with pins 12 passing through slots 11 and engaging the pawl swing in the same manner in which the same is engaged in the structure shown in the aforementioned United States patent.

The plunger 10 is provided with a recess 9 for the rocking arm 13, and with a spring 14 adapted to bear upon the base of the plunger casing; also like the device shown in the aforesaid patent. The plunger casing is composed preferably of one sheet of steel bent up as shown in Fig. 7, and provided with 75 projecting studs 15, one on each side and below a slot 16 in the side walls of the casing. The base of the casing 17 is turned at right angles out of the material of the back, as are also the sides 18, so as to form a three-sided 80 box, such as shown in Fig. 7. The plunger itself is provided with two projecting pins 19, which, upon the compression of the spring 14, may be inserted into the slot 16 in the side walls of the plunger casing. In order to 85 lock the plunger casing and plunger into position with the main frame, the plunger is depressed until the pins 19 of the plunger and the pins 15 of the casing occupy the position shown in Fig. 9, when they may be pushed 90 through the passage 8, and into the elongated slot 7. Upon releasing the plunger when the pins are in the slot 7, the spring will immediately secure the parts as shown in Fig. 1, in which position the parts will remain during 95 all usual operations of the machine. It will be noticed that the pins of the slot and the passage leading to the slot constitute a form of resiliently operated latch mechanism, which will automatically lock the plunger 100 and plunger casing to the main frame and the operating mechanism upon the mere insertion of the plunger and plunger casing into the space between the jaws of the main frame.

In carrying out this invention, details of 105 construction may be varied from those shown, and yet the essence of the invention be retained; some parts might be employed

without others, and new features thereof might be combined with elements old in the art in diverse ways, although the herein described type is regarded as embodying substantial improvements over such modifications.

As many changes could be made in the above construction, and many apparently widely different embodiments of the invention could be made without departing from the scope thereof, it is intended that all matter contained in the above description or shown in the accompanying drawings shall be interpreted in an illustrative and not in a limiting sense. It is furthermore desired to be understood that the language used in the following claims is intended to cover all the generic and specific features of the invention herein described, and all statements of the scope of the invention which as a matter of language might be said to fall therebetween.

We claim as our invention:—

1. The herein described numbering machine comprising a main frame, a shaft therefor, number wheels, pawl swing, plunger and operating means connecting said plunger and swing, a casing for said plunger adapted to fit the end of the main frame, but separable from said main frame, and spring operated pins on the plunger and plunger casing, and jaws to receive said pins in the main frame.

2. The herein described numbering machine comprising a main frame, receptive jaws thereon, a plunger, a shaft, number wheels, pawl swing, operative mechanism for connecting the pawl swing with the plunger, plunger casing adapted for attachment and detachment from the main frame, said plunger casing and plunger carrying pins for reception by said jaws.

3. The herein described numbering machine comprising a main frame, receptive jaws thereon, a plunger and plunger casing, a shaft, number wheels, pawl swing, operative mechanism for connecting the pawl swing with the plunger, the said plunger and

plunger casing adapted for attachment and detachment from the main frame, said plunger casing and plunger carrying pins for reception by said jaws, said jaws having elongated slots and passages communicating between said slots and the edge of the frame.

4. Mechanism for securing a detachable plunger and plunger casing to the main frame of a typographic numbering machine, consisting of jaw-like extensions of the main frame, elongated vertical slots therein, a passage communicating with said slots, and terminating at the edge of the jaws, pins resiliently held apart upon the detachable parts and adapted to be compressed for entrance into the passage, whereby upon reaching the slot at the end of the passage, they will be sprung apart by the spring.

5. A typographic numbering machine comprising a frame, number wheels and operative mechanism therefor, a plunger and plunger casing removable from said frame, and a resilient catch mechanism adapted to lock the plunger and plunger casing into place upon the proper placing of the same in operative relation with the main frame and operative mechanism.

6. A typographic numbering machine comprising a frame, number wheels and operative mechanism therefor, a plunger and spring, and plunger casing removable from said frame, and a resilient catch mechanism adapted to lock the plunger and plunger casing into place upon the proper placing of the same in operative relation with the main frame and operative mechanism, said resilient catch mechanism being operated by a spring, said spring being the normal plunger operating spring.

Signed at Brooklyn, New York, this 19th day of February 1909.

BENJAMIN B. CONRAD.
FRANK SANDER.
